(57) **CLAIM**

The ornamental design for a gun tool, as shown and described.

DESCRIPTION

FIG. 1 is a right side perspective view of a gun tool showing our new design; the left side perspective view is a mirror image of the right side view; the broken lines in the drawings depict parts of the gun tool that form no part of the claimed design.

FIG. 2 is a top view of the gun tool.

FIG. 3 is a bottom view of the gun tool; the broken lines in the drawings depict parts of the gun tool that form no part of the claimed design.

FIG. 4 is a right side view of the gun tool; the left side view is a mirror image of the right side view; the broken lines in the drawings depict parts of the gun tool that form no part of the claimed design.

FIG. 5 is a front view of the gun tool; the broken lines in the drawings depict parts of the gun tool that form no part of the claimed design; and,

FIG. 6 is a rear view of the gun tool; the broken lines in the drawings depict parts of the gun tool that form no part of the claimed design.

1 Claim, 5 Drawing Sheets
